UNITED STATES PATENT OFFICE

HOWARD EARL HOOVER, OF GLENCOE, ILLINOIS, ASSIGNOR TO THE HOOVER COMPANY,
A CORPORATION OF OHIO

ADVERTISING DISPLAY

Application filed January 24, 1929. Serial No. 334,848.

This invention relates to advertising devices and particularly to devices for advertising and displaying electric suction cleaners and operating parts thereof.

5 The primary object of the invention is to provide an advertising device of novel and improved construction which will demonstrate the suction power, or lifting capacity, of an electric suction cleaner.

10 Another object is to provide a device including a suction cleaner and parts connected thereto which will cause a weighted article to travel through certain predetermined positions by the suction created by the cleaner and then cause the object to return to initial position by gravity.

15 A further object is to provide a device including a suction cleaner and detachable parts thereof, which will continuously lift a steel ball by the suction of the cleaner during operation thereof and then release the ball at the limit of its upward travel, whereby the ball will be returned to initial position by gravity over a certain defined and interrupted route.

20 Other objects of the invention are to provide a device which will cause a steel ball to travel a predetermined position at the inlet of a suction hose where it will be lifted by suction from a suction cleaner; which will release the ball after it has traveled a certain distance and prevent it from coming in contact with the operating parts of the cleaner; which has a trap or valve which closes 25 of its own accord after the ball passes therethrough so as to maintain a suction in the hose; and which causes the ball to strike an obstruction and then fall into a receptacle where it will return to the inlet by gravity where the operation will again be 30 repeated.

Other objects and advantages will herein-after appear.

In accordance with the invention the device 35 has a frame or stand which supports an electric suction cleaner. A dusting hose which is secured to the frame has one end thereof connected to the cleaner and its other end connected to a tray or plate which 40 is arranged at the lower end of the frame.

The tray is provided with an inclined groove so that a ball or other object to be lifted by the suction of the cleaner will always be fed to the open end of the dusting hose. After the ball is carried through the hose it is returned to the tray by gravity and the operation is repeated. As the ball returns it strikes an anvil and bounces into a basket or other receptacle thereby attracting attention and making the device more interesting. 55 The ball is substantially as large as the internal diameter of the hose in order to permit proper lifting of the ball by preventing the air from being drawn around the sides of the ball.

60 The accompanying drawing illustrates a selected embodiment of the invention and the views therein are as follows:

Fig. 1 is a front elevation of the device.

Fig. 2 is a side view thereof.

70 Fig. 3 is a detail plan view on the line 3—3 of Fig. 1 showing the adapter connection.

75 Referring to the drawing, 5 designates generally a stand or frame comprising a face plate 6 and a supporting member 7 to which a suction cleaner 8 is rigidly attached. An adapter member 9 is secured to the eye of the fan casing 10 and is provided with a branch 11 to which a dusting hose or tube 12 is attached. A steel ball 13 is adapted to be 80 lifted by the suction in the hose 12 and a screen 14 fastened to a member 9, is arranged at the lower end of the fan casing to prevent the ball from coming in contact with a fan which operates in the casing 10.

85 After the ball is lifted by the suction in the hose 12 it will drop, due to its own weight, in the vertical portion 15 of the adapter 9 and cause a flap valve 16 to open and temporarily release the suction in the hose 12. An anvil 17 is located immediately below the valve so that when the ball drops through the valve it will strike the anvil and bounce into a catch basin, or other receptacle 18 where it will roll to the rearward side of the plate 6 into a 90 tubular member 19 and later be discharged on the tray 20 which is located at the lower end of the face plate 6.

95 The tray 20 is provided with a groove 21 which slopes toward the inlet end 22 of the

hose 12. After the ball passes through the tubular member 19 it will roll in the groove 21 to the inlet 22 where the suction in the hose 12 will again raise the ball and repeat the operation.

5 The hose 12 is preferably provided with a glass or other transparent portion 23 so that as the ball is being lifted by the suction in the hose its movement through the glass portion may be plainly seen. An opening 24 is provided through the face plate 6, and a light bulb 25 and a reflector 26 are arranged on the rearward side of the plate 6 to illuminate the glass portion 23 so that the upward movement of the ball as it passes therethrough may be easily seen.

10 The operation of the device is as follows:

15 The steel ball 13 is placed in the groove 21 in the tray 20 and rolls toward the inlet 22 of the hose 12, where it will be lifted by the suction until it reaches the top end of the hose and enters adapter 9 at the under side of the suction cleaner. After the ball has reached the end of its upward travel it will drop into the vertical portion 15 of the member 9 and fall through the valve 16. After passing through the valve 16 it will strike the anvil 17 and bounce into the catch basin 18. This catch basin is provided with an inclined portion 27 which leads to the end 28 of the tubular member 19 where the ball will descend by gravity to the plate 20 where the operation is again repeated.

20 The invention provides a device which is exceedingly interesting and demonstrates the lifting or suction power of a suction cleaner. The parts are properly positioned so that the steel ball will always travel the same way, and as it passes through the illuminated glass portion of the tube it will attract considerable attention.

25 Changes may be made in the form, construction and arrangement of the parts without departing from the spirit of the invention or sacrificing any of its advantages, and the right is hereby reserved to make all such changes as fairly fall within the scope of the following claims.

30 The invention is hereby claimed as follows:

35 1. A display device comprising a suction cleaner, a hose connected to said cleaner, an object adapted to be carried by the suction in said hose, means for returning said object to initial position, and means including 40 a catch basin and an anvil for interrupting said object during return thereof.

45 2. A display device comprising a stand, a hose mounted on one side of said stand, a tube mounted on the other side of said stand, 50 means for creating a suction in said hose, means adapted to be moved by the suction in said hose, and means including said tube for returning said second named means to initial posititon.

55 3. A display device comprising a stand, a

hose mounted on one side of said stand, a tube mounted on the other side of said stand, means for creating a suction in said hose, means adapted to be moved by the suction in said hose, means including said tube for returning said second named means to initial position, an anvil for interrupting the return of said second named means, and a catch basin for receiving said second named means after it is interrupted by said anvil and for feeding said object to said tube.

60 4. A display device comprising a stand, a hose mounted on one side of said stand, a tube mounted on the other side of said stand, means for creating a suction in said hose, an object adapted to be moved by the suction in said hose, means including said tube for returning said object to initial position, an anvil for interrupting the return of said object, a catch basin for receiving said object after it is interrupted by said anvil and for feeding said object to said tube, said hose having a transparent portion, and means for illuminating said transparent portion.

65 5. A display device comprising a stand having a face, a tray and a hose mounted on said face, a suction cleaner mounted on said stand and operatively connected to said hose, a tube mounted on the back of said stand, an object adapted to be carried from said tray to said cleaner by suction in said hose, means for releasing the object from said hose and cleaner, an anvil below said cleaner for deflecting said object after it is released, a catch basin communicating with said tube for receiving the object after it has been deflected, and means including said catch basin and said tube for returning the object to said tray.

70 6. A display device comprising a stand having a face, a hose and a tray mounted on said face, a suction cleaner mounted on said stand and operatively connection to said hose, a tube mounted on the back of said stand, an object adapted to be carried from said tray by suction in said hose, means for releasing the object from said hose, an anvil for deflecting said object after it is released, a catch basin communicating with said tube for receiving the object after it has been deflected, and means including said catch basin and tube for returning the object to said tray, said hose having a transparent portion, and means for reflecting a light through said transparent portion.

75 Signed at Chicago, in the county of Cook, and State of Illinois, this 15th day of January A. D. 1929.

HOWARD EARL HOOVER.
